CLAIM

The ornamental design for brick, as shown and described.

DESCRIPTION

FIG. 1 is perspective view of a first embodiment of a brick showing my new design;

FIG. 2 is right side elevational view thereof;

FIG. 3 is a top view thereof;

FIG. 4 is a front elevational view thereof;

FIG. 5 is a bottom view thereof;

FIG. 6 is a left side elevational view thereof;

FIG. 7 is a rear elevational view thereof; and,

FIG. 8 is a perspective view of a second embodiment of a brick shown on a reduced scale, it being understood that the rear and opposite of the front and side shown and that bottom are the same as the first embodiment shown in FIG. 5.
